UNITED STATES PATENT OFFICE

103,659

DESIGN FOR A DRESS

Maxwell Richter, New York, N. Y.

Application February 16, 1937, Serial No. 67,684

Term of patent 3½ years

To all whom it may concern:

Be it known that I, Maxwell Richter, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by the combination of tucks and pleats on the dress, as shown.

I claim:

The ornamental design for a dress, substantially as shown.

MAXWELL RICHTER.
